UNITED STATES PATENT OFFICE.

JOSEPH H. PILKINGTON, OF WATERBURY, CONNECTICUT.

PEN AND PENCIL CLIP.

No. 858,020.

Specification of Letters Patent.

Patented June 25, 1907.

Application filed January 19, 1907. Serial No. 353,080.

To all whom it may concern:

Be it known that I, JOSEPH H. PILKINGTON, a citizen of the United States, residing at Waterbury, county of New Haven, State 5 of Connecticut, have invented a new and useful Pen and Pencil Clip, of which the following is a specification.

This invention has for its object to provide a simple and inexpensive detachable clip for 10 fountain pens, pencils, etc., which may be readily attached to and detached from different sized pen barrels, pencils, etc., and may be readily attached to or detached from any article of clothing as a pocket, the 15 lapel of a coat, a waistband or suspender or a fold of a shirt or shirtwaist.

With these and other objects in view I have devised the novel clip of which the following description in connection with the accompanying drawing is a specification, reference characters being used to indicate the several parts.

Figure 1 is an elevation illustrating the use 25 of my novel clip in attaching a fountain pen to a garment, as for example to the outer side of a vest pocket; and Fig. 2 is a plan view corresponding therewith.

The special purpose of the present invention is to produce a clip of the character described which shall be neat and attractive in appearance, will meet every possible requirement of use and the parts of which may be produced by ordinary machinery and assembled at so low a cost that when made in quantities several of them may be made for a penny, thus enabling them to be sold at retail at a trifling cost and at a large profit to the manufacturer.

The clip comprises a band spring adapted 40 to engage different sizes of pen barrels and pencils and provided with an eye in which one end of a rod is rigidly secured, the other end of the rod being preferably provided with a smooth head.

10 denotes the spring which is simply a strip of spring metal bent to approximately circular form but left open, one end being preferably rounded, as at 11, and the other end turned backward and coiled to form an 50 eye 12 which in practice is set at a slight

angle to the axis of the spring. These springs with the eyes complete are produced at a trifling cost per gross.

13 denotes a rod one end of which is seated and rigidly secured in the eye, the other end being shown as provided with a rounded head 55 14. These headed rods are formed by means of a bolt-heading machine. The blanks are cut from a coil of wire and the heads upset thereon by what is practically a single operation and at a trifling cost per pound. The assembling of the headed rods and springs is performed mechanically, the feeding being either mechanical or by hand, as preferred, and the operation being performed at trifling 60 cost.

The operation in use will be readily understood from the drawing. The eye is set in the process of manufacture so that when the rod is inserted therein the head will be 65 thrown inward slightly so that its inner side will clamp one side of a pocket, a fold of garment, a waistband or the lapel of a coat against the pen or pencil by which the clip is carried. In the drawing, 15 represents a portion 70 of a garment, as a pocket, to which a fountain pen is attached by means of the clip. In ordinary use the clip remains upon the pen and is withdrawn therewith from the garment, but if preferred, the pen or pencil may 75 be withdrawn from the clip. The rod is rigid so that it can not become bent in use and the spring action is produced by torsion of the band spring.

Having thus described my invention I claim:

A clip of the character described comprising an open band spring having an eye at one end, and a rigid rod having one end secured in said eye and having a knob at its free end, 90 the inner side of the knob normally projecting inward to clamp a portion of a garment between it and the side of a pen or pencil removably mounted in said open band.

In testimony whereof I affix my signature, 95 in presence of two witnesses.

JOSEPH H. PILKINGTON.
